MASON'S LINE ANCHOR

John A. Edixon, Ashtabula, Ohio

Application July 28, 1947, Serial No. 764,052

2 Claims. (Cl. 33—85)

1

This invention relates to devices for supporting a mason's gage line or "course" line, while laying up walls.

In laying up a wall of concrete blocks, the mason stretches a cord or line for successive courses or layers, as a guide for positioning the blocks, so that the layers will all be parallel straight and horizontal and in vertical alignment. He does the same with bricks, hollow tile, etc.

The course line is usually located directly above the edge of the last course laid and parallel with it.

Usually the mason lays a pair of blocks at the opposite ends of the course to be laid, and contrives a way to attach the opposite ends of the line to these blocks, by nails, strips of wood or the like.

Such contrivances are troublesome to manipulate, are not stable and secure, are difficult to adjust to accurately position the line, and are liable to come loose or shift.

Mechanical clamp devices have been proposed which grip the end blocks with the line attached to the devices; but so far as I am aware, such devices have clamping jaws that grip the opposite sides of the block therebetween and variously comprise movable parts to make them adjustable to different over-all thicknesses of the blocks, bricks, tiles, etc., and are in fact mechanisms; and are expensive and troublesome to mount and adjust; and cumbersome to carry around.

Concrete blocks are hollow or have openings therethrough; the same is true of hollow tile; and bricks having holes through them are coming into more and more general use. Such holes or openings make of the block, etc., a structure having a relatively thin side wall.

The present invention is based on this fact.

In view of the foregoing, the object of the invention is to provide a simple device of the class referred to, which, without moving parts, will grip the aforesaid side wall of a concrete block, brick, tile, etc., and which is adapted to variations in thickness of said wall; and having a means for attaching a cord or line thereto which will dispose the cord in the correct indicating or gaging position when the device is in place, whereby adjustments and movable parts are obviated; and which device will be so simple in its functioning that it can comprise but a single piece or part; and be so small and compact in size that it can be carried in the mason's pocket; and be produced at small cost.

The invention is fully disclosed in the following description taken in connection with the accompanying drawing, in which:

Fig. 1 is a front view and Fig. 2 is a top view of an embodiment of the invention, and in the original drawing is life size;

Fig. 3 is a perspective view illustrating the device in use with concrete blocks or bricks;

Fig. 4 is a view to enlarged scale taken from the plane 4—4 of Fig. 3;

2

Fig. 5 is a top plan view of Fig. 4;

Fig. 6 is a view similar to Fig. 4 showing the adaptation of the device to hollow tile;

Fig. 7 is a view similar to Fig. 1 but to reduced scale illustrating a modification.

Referring to the drawing, Figs. 1 and 2, the device shown generally at A comprises an upper main body 1 from which depend three legs 2, 3, and 4, providing spaces 5 and 6 therebetween, and lower edges 7 and 8 on the body. The inner confronting edges 9 and 10 of the legs 2 and 3 are preferably but not necessarily parallel and rectilinear; as are also the edges 11 and 12 of the legs 3—4.

The corners where the legs join the body are relieved, as at 13, for clearance to be referred to.

In vertical alignment with the edges 10 and 11 are holes 14—15 in the body 1; and other holes may be provided as indicated at 16.

The device is all of one piece as shown and may be an aluminum casting, or a thick sheet metal stamping, or may be made from any other suitable material, for example a synthetic resin plastic.

In operation of the device, and as shown in Fig. 3, the mason, preparatory to laying a course of concrete blocks on the last course laid shown at 17—17, lays a pair of blocks 18 and 19 at the ends of the course 17—17, putting them in correct position.

The usual holes 20—20 in the blocks provide relatively thick walls at 21—21. In such case, a line or cord 22 is threaded through the middle hole 14 of one of the devices and secured by a knot 23 or otherwise; and the two legs 2 and 3 are straddled over the wall 21 at the block 18 until the body edge 7 rests on the wall 21.

Another one of the devices A is similarly mounted on the other block 19, with the cord 22 running through the hole 14 thereof; and the cord is then drawn taut, and the free end drawn taut through one of the other two unused holes, 15 or 16, for example the hole 16 as illustrated in Fig. 3; or through both of them successively; and this will secure it.

When the cord 22 is taut, the two devices A will be drawn toward each other; and each of them, may rock somewhat on the top of the wall 21 to bring the leg 2 into gripping engagement with the inner surface of the wall 21 and the leg 3 into engagement with the outer face 24 of the block. This rocking is illustrated in Fig. 5, where the device A is shown somewhat out of the horizontal.

However, as shown in Fig. 5 and indicated in Fig. 4, since the cord positioning hole 14 is in alignment with the leg edge 10, the cord 22 will be brought directly over the face 24 of the block whether the amount of rocking is small (solid lines in Fig. 5) or whether it is great (broken lines in Fig. 5).

By these provisions, the space 5 between the legs 2—3 can be made great enough for the legs to straddle the wall 21 of the block when it is

of maximum thickness in one lot of blocks; and they will then likewise straddle thinner walls of other lots of blocks; and in every case the cord 22 will be lined up with the face 24 of the block.

The relief at 13-13 on the device as will now be apparent allows the device to move down until the body edge 7 rests on top of the block and always come to the same elevation and not be irregularly held up by the corners at the top of the block wall 21.

If, from time to time, a spirit level laid on the courses to check them for horizontal alignment, shows that they are out of horizontal, this can be corrected by raising one end or the other of the line by raising one of the devices, since the legs 2-3 will grip the block wall 21 therebetween whether they are pushed all the way down or not; due to the tension in the line 22; and in Fig. 4 the device A is indicated by broken lines at one such elevated position.

The legs 2-3 and space 5 will fit and grip a range of block walls 21 of relatively great thickness as described.

The legs 3-4 and space 6 are provided to similarly grip walls of a range of less thickness for example the relatively thin walls of hollow tile as shown for the wall 25 of a hollow tile 26 in Fig. 6.

In the use of the device with such thin walls, the hole 15, aligned with the edge 11 of the leg 3, would be the one used to position the cord 22, as described hereinbefore.

Hollow bricks or bricks with holes in them will have walls of a thickness within the one or the other of the ranges above referred to, and therefore the device may be used for bricks with either pair of legs 2-3 or 3-4 as occasion indicates.

Instead of knotting the device at one end as indicated at 23, that end also may be secured by running it through any or both of the holes not being used; so that if preferred the line need not be knotted at any time.

As a further convenience of the device, when it is out of use, the cord may be wrapped around the body 1 and the free ends put through a pair of the holes 14-15-16 to keep it from unwinding.

While the device of Figs. 1 and 2 will take care of the whole range of thicknesses of wall encountered in different cases as described, the invention is not limited to a device having only two wall straddling spaces 5 and 6 but may have more if desired at somewhat greater cost.

In Fig. 7 is shown a modification to this end, as indicating the scope of the invention.

The body 27 has four legs 28-29-30-31 providing three successively narrower spaces 32-33-34. Holes 35-36-37-38-39-40 are provided in the body aligned respectively with the edges of the legs 28 to 31. When the space 32 is used, either the leg 28 or the leg 29 could be put in the hole and, correspondingly, the cord put in either the hole 36 or 35. When the space 33 is used, either the leg 29 or the leg 30 could be put in the hole, and correspondingly, the cord could be put in the hole 38 or the hole 37. When the space 34 is used, either the leg 30 or the leg 31 could be put in the hole, and, correspondingly, the cord could be put in the hole 40 or the hole 39.

While I have illustrated and described the preferred form of the invention, the invention is not limited thereto. Changes and modifications therein may be made. For example, while it is preferred to have the leg edges 9-10 and 11-12 parallel rectilinear edges; and to have the edges 7 and 8 continuous all the way between the said

leg edges, substantially the same positioning and gripping action will be performed by the device if the side edges of the legs have the contour indicated in broken lines, Fig. 1, at 9A to 12A and if the edges 7 and 8 provide a shoulder or shoulders as at 7A and 8A.

Other changes and modifications may be made and the invention comprises all of the same that come within the scope of the appended claims.

I claim:

1. A mason's line anchor comprising a duplicate pair of devices and a line, each device comprising: a plate-like portion generally of U-shape having a body and two elongated legs depending from the body when in the position of use, and the legs having mutually confronting parallel gripping faces; the legs being so spaced apart that the gripping faces may straddle and substantially fit and grip vertical spaced apart surface portions of a masonry block and cause the body to rest upon and be supported above the block; the body being provided with a plurality of spaced perforations therethrough, one of which is aligned with a said vertical surface of the block and disposed above the top of the block, when the body is supported on the block as aforesaid; the devices adapted to be thus mounted in spaced relation on spaced blocks in a course of blocks to be laid, the line being threaded through the aligned perforations of both devices and secured to one device and at the other device threaded through the other perforation thereof, and gripped by the joint gripping action of the two perforations on the line; the line being tensionable by drawing it farther through the two perforations of the said other device.

2. A device for use in duplicate in a mason's line anchor of the type comprising two spaced apart line holders and a line tensioned between them; the device comprising: a plate-like portion generally of U-shape having a body and two elongated legs depending from the body when in the position of use, and the legs having mutually confronting parallel gripping faces; the legs being so spaced apart that the gripping faces may straddle and substantially fit and grip vertical spaced apart surface portions of a masonry block and cause the body to rest upon and be supported above the block; the body being provided with a plurality of spaced perforations therethrough, one of which is aligned with a said vertical surface of the block and disposed above the top of the block when the body is supported on the block as aforesaid; the two aligned perforations of duplicates of the device when they are mounted on spaced blocks of a course to be laid, being sized to have a mason's course line threaded through both of them and secured at one end to one device and at the other end threaded through the other perforation of the other device, to cause the line to be gripped on the other device by the joint gripping action of the two perforations; the line being tensionable by manually drawing it farther through the two said perforations of the other device.
